[57] CLAIM

The ornamental design for a hot air and fume director for conveyor oven, as shown.

DESCRIPTION

FIG. 1 is a top, front perspective view of a hot air and fume director for conveyor oven, showing my new design.

FIG. 2 is a top, rear perspective view thereof.

FIG. 3 is a top plan view thereof.

FIG. 4 is a front elevational view thereof.

FIG. 5 is an enlarged cross-sectional view thereof taken along line 5—5 in FIG. 4 and viewed in the direction of the arrows.

FIG. 6 is a rear elevational view thereof.

FIG. 7 is a bottom plan view thereof.
